COIN OPERATED AMUSEMENT MACHINE

Dorcey A. Burns, Jr., 2672 Wilart Drive, Richmond, Calif.,
and J. Donald Durham, El Sobrante, Calif.; said Dur-
ham assignor to said Burns

Filed Oct. 14, 1965, Ser. No. 87,487

Term of patent 14 years

(Cl. D34—5)

FIGURE 1 is a front perspective view of a coin operated amusement machine.

FIGURE 2 is a front elevation thereof.

FIGURE 3 is a right end view thereof.

FIGURE 4 is a left end view thereof.

The rear of the coin operated amusement machine is plain and unornamented.

The dominant features of our design reside in those portions shown in full lines on the drawings.

We claim:

The ornamental design for a coin operated amusement machine, substantially as shown and described.
